FLUSH TYPE TOGGLE LATCH

Arnold F. Gander, Berkeley, Calif.

Application March 15, 1945, Serial No. 582,866

2 Claims. (Cl. 292—223)

1

This invention relates to latch mechanisms and particularly to those of a type adapted to quick release and to uses such, for example, as the latching of doors covering inspection openings in aircraft, automobiles and the like.

A general object of the invention is to provide an improved and rugged latching mechanism which, although light in weight and made of a relatively few parts is also dependable in operation and to hold firmly when latched in spite of vibration and jolts.

The present invention has for another object the provision of a latch mechanism having only the operating element thereof exposed to the outer surface of the part upon which it is mounted and being flush therewith.

Another object of this invention is to provide a latch mechanism having an exposed operating element so constructed and arranged that it forms a seal against the weather and elements when closed and is not rendered inoperative by bad weather conditions.

It is a further object of the invention to provide an improved latch mechanism adapted to use in connection with the closure for inspection openings of aircraft and the like, and which is compact and may be manufactured at low cost without sacrificing dependability of operation and long life.

In one of its more specific aspects, my invention has for an object the provision of a latch mechanism including an actuating element upon which forces normally encountered in use, such as air pressure, tend to neutralize or balance on two sides of the element.

Other objects and advantages of the invention will be apparent from the following description and the accompanying drawings, in which similar characters of reference indicate similar parts throughout the several views.

Referring to the drawings of which there are two sheets:

Fig. 1 is a fragmentary side elevational view of one side of a wall section of an airplane or the like, showing one type of door to which a preferred embodiment of my latch mechanism is attached;

Fig. 2 is an enlarged fragmentary view looking at the opposite side of the door from that shown in Fig. 1 which depicts a preferred form of my latch mechanism in rear elevation;

Figs. 3 and 4 are sectional views of the door and latch mechanism indicated in Figs. 1 and 2 wherein the section for both views is taken along the line 3—3 of Fig. 2 and Fig. 3 shows the

2

latch mechanism in a holding position and Fig. 4 shows the latch mechanism in a retracted position;

Figs. 5 and 6 are respectively sectional views taken substantially on lines 5—5 and 6—6 of Fig. 2;

Fig. 7 is a view similar to Fig. 1 which shows the adaptation of a modified form of my invention to the door structure of an airplane or the like;

Fig. 8 is a view of the modified form of my invention shown in Fig. 7 drawn to a larger scale and disclosing the side opposite from that shown in Fig. 7;

Figs. 9 and 10 are sectional views, with the sections for both being taken substantially along the line 9—9 of Fig. 8, and wherein Fig. 9 shows the latch mechanism in a holding position and Fig. 10 depicts the latch mechanism in a retracted position; and

Figs. 11, 12 and 13 are respectively sectional views taken substantially on lines 11—11, 12—12 and 13—13 of Fig. 9 and viewed in the direction indicated by the arrows.

Referring to the illustrative embodiment of my invention which is shown in Figs. 1 to 6 inclusive, my preferred form of latch mechanism 20 is indicated in its adaptation to the releasable holding of a door 22, which door is swingably

supported with respect to a wall 23 by a hinge 24 so as to provide a closure for an opening 25 in the wall. The wall indicated comprises an outer covering or skin 26 which has secured to the inner surface thereof a door jamb 27 against which the edges of the door seat to provide a substantially tight closure for the opening. Preferably near the edge of the door opposite that which is hingedly supported, an aperture 28 is provided for access to the latch mechanism 20 and manual operation thereof from the outside of the door.

In its preferred form, the latch mechanism 20 includes a base 29 having mounting flanges 30 and integral supporting flanges 32. One surface 45 of the base 29 opposite the side from which the supporting flanges 32 project is flat or adapted to conform closely to the inner surface of the door 22. An aperture 33 in the base 29 is somewhat larger than the aperture 28 in the door and is concentrically disposed with respect to the aperture 28 to provide a sealing surface 34 around the aperture 28 when the base is secured to the inner surface of the door by suitable fastening means such as rivets 35.

Desirably the supporting flanges 32 have parallel

lel end portions 36 and 37 at their opposite ends, while the intermediate portions are curved outwardly around the aperture 33. Rotatably mounted between the supporting flanges 32 by pin 38 is a latch actuator 39. The pin 38 extends through the parallel end portions 37 and a bearing portion 40 at one end of the actuator 39 and is secured in place by suitable means such as a cross pin 42. The actuator 39 has integral flanges 43 extending across the inner surface thereof from the bearing portion 40 in spaced and parallel relation. In alignment with the aperture 28 the actuator 39 has a protruding mid-portion 44 adapted to fit into the aperture 28 and an integral projecting flange 45 surrounding the protruding portion which conforms to and seats against the sealing surface 34 to provide a sealed closure for the aperture 28 when the latch mechanism is in the holding position as shown in Fig. 3. In order to preserve a smooth and streamlined outer surface, the protruding mid-portion of the actuator is flush with the outer surface of the door when the flange 45 is seated against the sealing surface 34. Thus the actuator is exposed for operation from the outside of the door and provides a substantially weather-proof seal for the access aperture 28 when the door is closed and held by the latch mechanism.

The actuator 39 is biased to the closed position by a torsion spring 46, which spring, by preference, has side loops 47 encircling the ends of the bearing portion 40; an intermediate connecting portion 48 which connects the loops and engages the base 29 and extending ends 49 which lie along the sides of the flanges 43 and engage the rear surface of the actuator 39.

Adjacent the swinging end of the actuator 39, a latch bolt 50 is supported for rotary swinging movement relative to the base by a pin 52 which extends through the parallel end portions 36 of the flanges 32 and a bearing portion 53 of the latch bolt. The pin 52 is secured in place by fastening means such as a cross pin 54. The latch bolt 50 has an integral latching portion 55 and is swingable about the axis of the pin 52 to a holding position in which the latching portion engages a keeper 56 secured to the door jamb by fastening means such as rivets 57. The holding position of the latch bolt 50 is illustrated in Fig. 3. When swung to a retracted position, such as that illustrated in Fig. 4, the latch bolt 50 disengages the keeper 56 and allows the door to swing open.

Actuation of the latch bolt 50 by manual movement of the actuator 39 is effected through a connection between the latch bolt and the swinging end of the actuator which is provided by a link 58. At one end the link 58 is rotatably connected to the latch bolt at a position displaced from the axis of the latch bolt supporting pin 52 by a pin 59. The other end of the link is rotatably connected to the swinging end of the actuator by a pin 60 which extends through the actuator flanges 43. In the retracted position of the latch bolt which is illustrated in Fig. 4, an integral stop 62 on one side of the outer surface of the bearing portion 53 of the latch bolt engages a co-acting stop 63 on the end surface of the link 58 to prevent movement of the latch bolt beyond a position in which the axes of the pins 59 and 60 are in substantial alignment with the axis of the pin 52.

By the disclosed construction and arrangement of parts, the actuator 39 serves as a part of a

toggle connection by which the latch bolt 50 is firmly urged to its holding position so as not to be affected by vibration or jarring, while the latch bolt itself serves as a part of another toggle connection which holds the latch bolt in a retracted position against the biasing force of the spring 46 when operated thereto by manual movement of the actuator 39.

The function of the toggle connection for holding the latch bolt 50 firmly in engagement with the keeper 56 may be understood by reference to Fig. 3. As there illustrated, when the latch bolt 50 is in the holding position the axes of the pins 59 and 60 which provide the connections of the link 58 to the latch bolt and actuator, respectively, approach alignment with the axis of the pin 38 upon which the actuator is rotatably supported. If it is desired that the latch bolt shall be securely held in the holding position when the actuator is in the holding or closed position, the parts may be so constructed that the axis of the pin 60 is actually aligned with the axes of the pins 59 and 38 or crosses the line between the axes of the pins 59 and 38. In this instance, however, the door cannot be closed when the latch bolt is in the holding position without retracting the latch bolt by manual operation of the actuator 39. In the disclosed form, wherein the axis of the pin 60 approaches alignment with the axes of the pins 59 and 38, the engagement of the angularly disposed edge 64 of the latch bolt with the door jamb applies a component of force through the link 58 to move the actuator against the biasing force of the spring 46, permitting closure of the door and automatic latching operation when the latch bolt is in the holding position.

As illustrated in Fig. 4, the latch bolt 50 is retained in the retracted position when actuated thereto by manual movement of the actuator 39 by virtue of the alignment of the axes of the pins 52, 59 and 60 which support the actuator and the link 58. It is understood, of course, that the axis of the pin 59 may either be in alignment with the axes of the pins 52 and 60 when the stops 62 and 63 are in contact or may pass slightly beyond that position of alignment. If it were desired that the latch mechanism should automatically return to the holding position after manual release, the axis of the pin 59 would approach but would not reach alignment with the pins 52 and 60; in which instance the spring 46 would return the latch bolt to the holding position. With the disclosed latch mechanism in which the actuator and latch bolt are retained in the retracted position after manual operation thereto, it is reset for holding the door closed by manual movement of the actuator or link to upset the alignment of the axes of the pins 52, 59 and 60 from the inside of the door.

For purposes of illustrating the construction and operation of the modified form of my latch mechanism disclosed in Figs. 7 to 13, inclusive, the wall, door and keeper structures may be considered similar to those previously described and are referred to by like reference numerals. Although there are many features of similarity between the two disclosed latch mechanisms, such as the flush mounting of the latch mechanism with the outer surface of the door, the weather-proof sealing of the access openings by the latch actuating parts and the use of toggle connections for retaining the latch bolt and actuator in the holding or retracted positions when manually operated thereto, the modified form of my latch

mechanism shown in Figs. 7 to 13 inclusive has an actuator 70 which permits full manual control of the latch mechanism from outside the door. In this instance, the door has two openings 72 and 73 which are desirably near the side thereof opposite the hinge 24 and are spaced for alignment with manually operable contact or button portions 74 and 75 of the actuator 70.

For supporting the latch mechanism 76 in an operative position adjacent the openings 72 and 73 in the door, it includes a base 77 which has mounting flanges 78 secured to the inner surface of the door by fastening means such as the rivets 35 as well as inwardly extending and substantially parallel supporting flanges 79. One face of the base 77 conforms to the surface of the door against which it is mounted. In the mid-portion of the base and between the supporting flanges 79 is an opening 80 of a smaller size than the opening 72 in the door and which is substantially concentric with respect to the opening 72 to provide a sealing surface 82 for seating engagement with the button portion 74 of the actuator.

The latch actuator 70 has oppositely extending end portions or arms 83 and 84 which carry the button portions 74 and 75 respectively in positions for alignment with the openings 72 and 73 and is rotatably supported intermediate its ends by a pin 85 which extends through the supporting flanges 79 and a bearing portion 86 of the actuator. The pin 85 is secured in place by fastening means such as a cross pin 87. The extending end or arm 83 of the actuator is curved and extends outwardly through the opening 80 for movement of the button portion 74 toward and from the outer surface of the door, while the arm 84 carries the button portion 75 for movement toward and from the inner surface of the door.

The thickness of the button portion 74 is such that when it is seated against the sealing surface 82, its surface is flush with the outer surface of the wall. The button portion 75 has a protruding mid-portion 88 adapted to fit into the opening 73 and has an integrally flanged outer edge providing a sealing surface 89 which seats against the inner surface of the wall adjacent the opening 73. By this arrangement of structure, both openings 72 and 73 are closed and sealed by their respective button portions of the actuator and present surfaces flush with the outer surface of the wall when the latch mechanism is in the holding position, as shown in Fig. 9. In addition, and since the button portions 74 and 75 are on opposite sides of the actuator support pin 85, the effect of air pressure against the two button portions tends to balance so as to avoid a tendency for the air pressure to effect an undesired release of the latch mechanism.

A latch bolt 90 is rotatably supported between the supporting flanges 79 adjacent the end of the arm 83 of the actuator by a pin 92 which extends through the supporting flanges and a bearing portion 93 of the latch bolt. The pin 92 is held in position by suitable means such as a cross pin 94. As in the previously described form of my invention, the latch bolt includes an integral latching portion 95 for engagement with the keeper 56 to hold the door in the closed position, as shown in Fig. 9.

At a position displaced from the axis of the latch bolt support pin 92, the latch bolt is rotatably connected to one end of a link 96 by a pin 98. The other end of the link 97 is rotatably

connected to the arm 83 of the actuator by a pin 98 so that the link forms an actuating connection between the actuator 70 and the latch bolt 90. In addition to the link 96, and to provide a biasing force for holding the latch bolt in the position to which it is last manually operated, a bowed compression spring 99 has one end anchored to the latch bolt support pin 92 and its other end connected to the pin 98.

In one position of the actuator 70, such as the closed or holding position indicated in Fig. 9, the pin 98 by which the link is connected to the actuator arm, is on one side of a toggle action line passing through the axes of the pins 92 and 85 upon which the latch bolt and actuator respectively are supported. In this position of the actuator, a component of the biasing force of the spring 99 biases the actuator in a direction which maintains the seated relation of the button portions 74, 75 with their respective sealing surfaces. In the other position of the actuator which is shown in Fig. 10, the pin 98 and the end of the spring 99 which is connected thereto have crossed the action line of the toggle passing through the axes of the pins 92 and 85 and a component of the force of the spring 99 biases the actuator to the open or retracted position. Thus, the arm 83 of the actuator and the compression spring 99 provide a toggle connection for maintaining the latch mechanism in the position to which it is last operated.

In the holding position of the latch mechanism shown in Fig. 9, the axes of the pins 97 and 98 at the ends of the link 96 are in substantial alignment with the axis of the pin 85 which supports the actuator. This alignment of the axes of the pins 97, 98 and 85 substantially locks the latch bolt in the holding position firmly to maintain that position against any possible effects of vibrations or jarring when the door is closed and prevents the closing of the door without manipulation of the actuator when the latch bolt is in the holding position. Thus the arm 83 of the actuator and the link 96 form parts of a second toggle connection which has a controlling influence upon the operation of the latch mechanism.

Quick release of the door for opening is effected from outside the door by manual force applied to the button portion 75 of the actuator. Closing of the door and its retention in the closed position by the latch mechanism is effected by pushing the door shut and then applying force to the button portion 74 of the actuator.

From the foregoing description of the structure and operation of both of the disclosed forms of my latch mechanism, it may be understood that each includes a combination of toggle connections wherein the actuator serves as a part of the operating mechanism in addition to providing an exposed element for the manual operation of the latch. In both forms of the latch mechanism, the exposed portion or portions of the actuator are flush with the outer surface of the door so as to preserve the streamlined surface. In addition, the joints between the actuator and door are sealed by the engagement of unexposed surfaces so as to be weather-tight and operable in adverse weather conditions. In each latch mechanism the disposition of parts is such that the latch bolt is firmly held in the holding position so that jolts and vibration cannot provide an undesired release of the latch. Both latches may be quickly operated and each remains in the

position to which it is last operated until that position is manually changed.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A latch mechanism comprising, in combination, a base including mounting flange portions and supporting flanges, said base having an opening therein between the supporting flanges, a latch actuator rotatably secured to the base between the supporting flanges for limited swinging movement about a fixed axis, said actuator having manually operable actuating portions on opposite sides of the said axis of swinging movement therefor, one of said actuating portions extending through said opening in the base, a latch bolt rotatably secured to the base by a support pin for swinging movement between holding and retracted positions, a link rotatably connected to the actuator and to the latch bolt at positions such that the axes of the rotatable connections to the link are substantially aligned with the axis of swinging movement of the actuator when the latch bolt is in said holding position, a compression spring having one end anchored to said support pin and its other end connected to the actuator at a position such that the action line of the spring crosses a line between the anchored end of the spring and the axis of swinging movement of the actuator whereby said actuator is biased toward the limit of swinging movement to which it was last operated.

2. In a latch mechanism adapted for mounting flush with the outer surface of a door of an airplane or the like having adjacent openings for the accommodation of parts of a latch actuator, the combination comprising a base having an opening therein smaller than one of the openings in the door and mounted on the inner surface of the door adjacent said one of the openings and providing an inner sealing flange, a latch actuator

having oppositely extending end portions for operating the mechanism to holding and retracted positions, one of said end portions extending through said opening in the base and having means thereon fitting into said one of the openings in the door in flush relationship to the outer surface of the door and engaging said inner sealing flange in one position of the latch actuator, the other of said end portions including a portion fitting into the other of said openings in the door in flush relationship to the outer surface of the door and having an edge sealing flange engaging the inner surface of the door in said one position of the latch actuator, and means rotatably connecting the latch actuator to said base intermediate said extending end portions for swinging movement of said end portions toward and from the openings in the door.
